UNITED STATES PATENT OFFICE

RICHARD B. PARKER, OF SKANEATELES, NEW YORK, ASSIGNOR TO SAMUEL E. DARBY,
TRUSTEE, OF NEW YORK, N. Y.

GRATE CONSTRUCTION

Application filed December 14, 1926. Serial No. 154,698.

This invention relates to a novel grate construction for use in retorts.

One of the objects of this invention is the provision of a grate made up of a plurality of independent grate bars of a construction adapted to distribute a gas to the fuel bed.

Another object of this invention is the provision of a series of gas boxes adapted to support the grate and arranged in conjunction therewith to supply a gas to the fuel bed at any desired point.

A further object of the invention is the construction of a combination grate structure and gas distributing boxes, having a suitable support therefor.

Another object of the invention is the provision of an apparatus for supplying gas to these boxes.

These and many other objects which will become apparent as the description proceeds, are sought and obtained by the principles involved in the construction to be described hereinafter.

This invention resides substantially in the construction, combination, arrangement and relative location of parts as will be described in this specification.

Referring to the drawings in which the same reference numerals will be used in the several views to indicate the same parts, Figure 1 is a plan view of the grate showing several parts to which this invention does not relate;

Figure 2 is a vertical cross-sectional view of the grate structure mounted within the retort.

Figure 3 is a side elevational view of a grate bar mounted on one of the gas boxes, which is shown in cross-sectional view.

Figure 4 is a cross-sectional view of a grate bar and an enlarged side elevational view of one end of the grate bar.

In many processes for the treatment of materials within a retort it has been found desirable to supply a suitable gas or even a liquid to some particular part of the fuel bed, or at times to the whole fuel bed to increase the efficiency of the process. For one instance of this reference may be made to the process of treating carbonaceous materials of all kinds by a heat treatment to extract there-

from the volatile constituents. A complete process of this nature and the apparatus for carrying it out has been disclosed in my co-pending applications, Serial Nos. 154,694 and 154,695, filed respectively on December 14, 1926 and December 14, 1926.

Referring to Figure 1, the base of the retort in which the grate is mounted has been shown at 1. A top plan view of the grate 2 is shown over the surface of which the cutter bar 3 is operated by means of the oscillating carriages 4. This movement of the carriages is accomplished by means of the worm wheels 5, driven through the shaft 6 and the gear 7. The cutter bar mechanism forms no part of this invention as it has been fully covered in the above mentioned applications. It is, of course, to be understood that the particular grate and box construction disclosed herein is adapted and intended to be used in any retort.

Referring to Figure 2, there is shown extending across the grate chamber the supporting beams 8 on which are mounted a plurality of gas or distributing boxes 9 which are each divided into smaller sections by the internal walls 10. Passages 11 are provided in the walls and the top of the boxes. A series of short pipes 12, one for each of the boxes is connected to the main pipe 13. In connection with this piping system, it may be stated that valves 20 may be inserted in the pipes 12 and in the pipe 13, at suitable points to provide means for controlling the admission of gas to any or all of the boxes. These valves have not been shown for the sake of simplicity, but their application to this invention is at once apparent to those skilled in the art.

The grate structure proper comprises a plurality of grate bars 2, which are of triangular cross-section and hollow. At the apex of the grate bars or distributed along the top thereof is a series of small openings 14 through which the gas may be delivered to the fuel bed. Each of the grate bars is provided near its end with the projection 2' which are spaced apart a distance equal to the length of the gas boxes to provide a means for centering the bars on the grate boxes. In Figure 2,

a small section of the hopper 15 has been shown supported beneath the grate structure, but this forms no part of the present invention.

5 The operation of this arrangement will be apparent from the foregoing description, but it may be stated that any suitable gas or even an inflammable liquid could be supplied through the pipe 13 to anyone of the gas 10 boxes and distributed therefrom through the openings in the boxes and grate bars to any point in the fuel bed. By supplying an inflammable gas or liquid to the heated materials on the grate, it will be seen that the 15 burning or oxidizing action may be controlled. However, this is no part of the present invention.

I am aware, of course, that many changes 20 in the details of construction and relative arrangement of parts will readily occur to those skilled in this art, and I do not, therefore, desire to be limited to the particular construction shown for purposes of illustration, but rather to any structure embodying 25 the principles of this invention which will come within the terms of the appended claims.

What I seek to secure by United States Letters Patent is:

30 1. In a grate structure for supporting a bed of solid fuel the combination with a plurality of hollow bars of V-cross section having openings in the walls and projections at the base thereof of a plurality of 35 boxes, having openings therein, for supporting said bars, said projections being arranged to center the bars on the boxes and means for distributing a gas to said boxes, the gas flowing from said boxes and through 40 said bars into the fuel bed.

2. In a grate structure for supporting a bed of solid fuel the combination with a plurality of hollow bars open at the bottom and having holes in the walls thereof near the 45 top, of a plurality of boxes supported under said bars and having a plurality of holes in the tops thereof, conduits connecting said boxes to a feed line and means in said conduits for controlling the area of delivery of 50 gas to the grate.

3. In a grate structure for supporting a bed of solid fuel the combination with a plurality of hollow bars open at the bottom and having holes in the walls thereof near 55 the top, of a plurality of boxes supported under said bars and having a plurality of holes in the tops thereof, a pipe leading from each of said boxes and a conduit leading to each of said pipes.

60 4. In a grate construction of the type described, the combination with a plurality of grate bars arranged to support a bed of solid fuel, said bars having openings therethrough of a plurality of apertured boxes arranged to 65 support said bars and pipe connections to said

boxes through which gas may be delivered to and through said boxes and bars and into a fuel bed on said bars.

5. A grate construction for supporting a bed of solid fuel comprising in combination 70 a plurality of grate bars of V-cross section having openings in the walls thereof, a plurality of boxes having openings in the top thereof, said bars being supported in inverted position on said boxes, and means 75 for distributing a gas through said boxes and bars to any desired area of the grate.

In testimony whereof I have hereunto set my hand on this 11th day of December, A. D., 1926.

RICHARD B. PARKER.
